UNITED STATES PATENT OFFICE.

EMIL JOSSE, OF BERLIN, AND PAUL CHRISTLEIN, OF CHARLOTTENBURG, GERMANY.

ELASTIC-FLUID TURBINE.

1,073,421.

Specification of Letters Patent. Patented Sept. 16, 1913.

Application filed May 20, 1912. Serial No. 698,481.

To all whom it may concern:

Be it known that we, EMIL JOSSE and PAUL CHRISTLEIN, subjects of the German Emperor, and residing at Berlin and Charlottenburg, near Berlin, Germany, respectively, have invented certain new and useful Improvements in Elastic-Fluid Turbines, of which the following is a specification.

The object of the present invention is an elastic fluid turbine.

Figure 1 is a diagram of the curve representing the velocity coefficient of a jet of steam. Fig. 2 is a diagrammatic view of the results obtained by the inclination of the outlet to the geometrical axis of the guide plates. Figs. 3 and 3^a show the formation of a conduit having a normal section, the space between the conduit and the rotor being covered by projecting rings of the rotor. Figs. 4 and 4^a are similar views illustrating the covering of the space by projecting rings of the conduit. Figs. 5 and 6 represent the conduits and nozzles with walls receding from the normal outlet.

Experiments made by the applicants have proven that the velocity coefficient of a jet of steam is dependent on the theoretical velocity developed in a given conduit at a fixed expansion ratio and is represented by a curve *a*, Fig. 1, showing a pronounced maximum and declining toward both sides from this maximum. The form of that branch of the curve adjacent to zero is determined first, by the greatest specific gravity and second, by the diffusing action of the conduit, and third, by the recoil of condensation and the sound vibrations in the elastic medium at a velocity exceeding the critical sound velocity.

The form of the other branch of the curve is determined by the deflection of the axis of the outflowing jet from the geometrical axis of the conduit, and deflections of 50 degrees and over are possible. This deflection of the axis is the result produced by the customary travel section of the guide plates *i. e.* by the inclination of the outlet to the geometrical axis of the guide plates. The results produced by these experiments are illustrated in Fig. 2. In this figure *c* represents the curve of the coefficient of velocity of a nozzle having a predetermined opening ratio and the customary beveled section; *c'* is the curve of the velocity coefficient of the same nozzle but having a normal section. In order to increase the effi-

ciency of the turbine according to the present invention the deleterious effect of the beveled section of the conduit or nozzle is avoided by suitably shaping the outlet 60 thereof.

Figs. 3 and 3^a of the drawings show the formation of a conduit having a normal section instead of an advanced section, the space or jet between the conduits and the 65 rotor being covered by projecting rings of the rotor. Figs. 4 and 4^a show a similar construction, the covering of the space however, being effected by projecting rings of the conduit, while in Figs. 5 and 6 the conduits and 70 nozzles are shown with walls receding from the normal outlet. As shown in Figs. 3 to 75 4^a the outlet walls 13 of the guide plates are not arranged in a common plane parallel to the plane of the wheel, but are arranged vertically to the geometrical axis of the 80 blades. By using a high jet velocity (a velocity exceeding the critical velocity) in conjunction with the low specific gravity of the medium and by dispensing with large surfaces for the surface friction of the steam, a further increase of the velocity coefficient relatively to that coefficient corresponding to the conduit having the customary beveled section, is obtained. When arranging the outlet of the conduit at right angles to the geometric axis, it is preferable 85 in order to avoid considerable losses of power at the jets, to arrange a ring 14 covering the common jets and an inner protecting ring 15 preventing the auxiliary jet of steam produced by the centrifugal action to produce a disturbance of the working steam jet. In Figs. 4 to 4^a the same result is obtained by stationary inner and outer protecting rings 14' and 15' on the conduit. 90 Finally, it is preferable with axial turbines to make the middle admission diameter of the conduit of about 8 to 10 mm. smaller according to the size of the jet than that of 100 the rotor for the purpose of obtaining a central admission with a minimum height of the blades, in order to still further reduce the losses of power at the jets. The difference between the diameter of admission of 105 the conduit and that of the rotor is designated in Figs. 3 and 3^a or 4 and 4^a respectively, at *d*.

Instead of shaping the conduit as shown in Figs. 3 and 3^a or 4 and 4^a it may be shaped 110 as illustrated in Fig. 5. In this figure is shown the usual conduit with parallel walls.

16 denotes the upper faces of the blades and 17 the rear faces of the blades. The upper faces 16 of the guide blades serve as the customary guide faces for the jet, while the 5 rear walls 17, as well as the adjacent faces, are only extended as far as to the normal outlet 18 and then recede from that point. The jet e can now freely develop into a parallel jet at two expansions or into a diverging jet with so-called gap expansion. The surface friction is thereby substantially reduced as a considerable portion of the surface is removed just at the place of the highest velocity of the steam. A correct feeding 10 must continuously be maintained and the so-called jet expansion may be considered admissible to a great extent which is very important during the high pressure stages of a turbine, at which as it is known, with the 15 reduction in the efficiency and increase of the available fall is produced. The back of the blades gradually slanting from the normal outlet to the end of the conduit may follow a suitable curve 19. The additional 20 expansion of the end outlet cross section denoted with f in Fig. 5 is suitably chosen in such a way that with the greatest available fall a deflection of the axis of the jet can thus take place.

25 Analogous the above invention can be employed where a nozzle with an expansion extension is used as conduits. This is illustrated by way of example in Fig. 6. The expansion ratio in the nozzle

$$35 \quad \frac{F}{F_m}$$

is calculated for example for the normal or most frequently employed pressure ratio

$$40 \quad \frac{p'}{p^2}$$

45 of the corresponding stage in the working phase of the turbine, thus at the outlet from the normal section 19 a parallel jet is formed

ing. The wall 19 recedes from this point along a suitable curve as shown in the drawing by the row of nozzles succeeding each other.

I claim:

1. In an elastic fluid turbine of the character described, in combination with the rotor thereof having buckets, inlet nozzles having all of their walls cut back for providing a clearance at those portions which extend 50 beyond the end of the nozzle proper and terminating on a plane perpendicular to the direction in which the nozzle is pointing and in close proximity to the entrance portion of the bucket of the rotor, said nozzles 55 having outlets of rectangular cross-section issuing a single undivided jet in the direction of the geometrical axis of the nozzle, substantially as described.

2. In an elastic fluid turbine of the character described in combination with the rotor thereof having buckets, inlet nozzles terminating in a plane perpendicular to the direction in which the nozzle is pointing and in close proximity to the entrance portion 60 of the bucket of the rotor, said nozzles having outlets of rectangular cross-section issuing a single undivided jet in the direction of the geometrical axis of the nozzle, substantially as described.

3. In an elastic fluid turbine of the character described in combination with the rotor thereof having buckets, inlet nozzles of rectangular cross-section provided with walls cut back for providing clearance at the portions extending beyond the end of the nozzle proper for producing a non-dispersing 75 jet of rectangular cross-section.

In testimony whereof we affix our signatures in presence of two witnesses.

EMIL JOSSE.
PAUL CHRISTLEIN.
